TWISTING MACHINE

Raymond E. Getchell, Holyoke, Mass., assignor to
 B. F. Perkins & Son, Inc., Holyoke, Mass., a
 corporation of Massachusetts

Application January 19, 1934, Serial No. 707,237

8 Claims. (Cl. 117—47)

This invention relates to improvements in twisting apparatus and is directed more particularly to improvements in machines and a method for forming a cable or cord by twisting together 5 a plurality of twisted strands which strands are formed by twisting a plurality of elements about one another.

The principal objects of the invention are the provisions of a machine and a process for accurately and uniformly twisting a plurality of elements or filaments into separate strands which are then twisted together to form a continuous body or cord. The machine of the invention is constructed and arranged in a novel manner so 10 that a completed cable or cord is formed by successive and continuous operations, thereby obviating a number of the separate operations necessary in prior art practice, all to the end that there results efficiency in operation and a 15 saving in the manufacturing costs of the cable or cord.

Accuracy and uniformity of twisting are important features of the invention and facilitate the producing of a cord or cable which is not 20 only uniform in all its important respects but which possesses a maximum of strength. This is accomplished by the provision of novel means for feeding out plural elements from packages, forming these into strands and the strands 25 into a cord or cable and taking up the finished cable at definite predetermined rates, all of which insures definite twisting results with uniform and constant conditions of tension.

One important feature of the invention is the 30 provision of a process wherein separate packages may each contain plural elements or yarns, the elements from each of the packages being twisted to form strands which are subsequently twisted to form a cord or cable by a continuous process. 35 The elements are twisted and delivered to the strand twisting mechanism in such a way that the operation of strand twisting is in no way interfered with by the operation of twisting the elements into strands, novel means being employed to tension and feed the elements and the 40 strands.

The machine of the invention comprises a novel combination and arrangement of parts so as to be simple in form and yet efficient in its 45 operation. By reason of the many novel features thereof it is not necessarily limited to but is particularly adapted for the forming or producing of small cables or cords such as cords used in tire manufacture. In connection with such a product as mentioned, it is necessary that the

cord be produced economically and uniformly while it must possess maximum strength and stretchability consistent with its size. To attain all of this, the machine embodies certain novel features of construction and arrangement of parts which co-operate to produce the desired 5 results.

Various and numerous objects and advantages of the invention will be hereinafter more fully referred to in connection with the accompanying 10 description of the present preferred form thereof, reference being had to the accompanying drawings, which illustrate the present preferred embodiment of the invention. In the drawings,

Fig. 1 is a front elevational view of a machine 15 embodying the novel features of the invention.

Fig. 2 is an end elevational view of the machine shown in Fig. 1 taken at the left-hand end thereof.

Fig. 3 is an elevational sectional view taken on 20 the line 3—3 of Fig. 1.

Fig. 4 is a combined sectional and elevational view through one of the package spindles and the twisting head.

Fig. 5 is a plan view showing the twisting head 25 and feed out mechanism.

Fig. 6 is an enlarged sectional view on the line 6—6 of Fig. 4.

Fig. 7 is an enlarged sectional view through 30 the upper end of the twisting head.

Fig. 8 is a fragmentary elevational view of the inside of one of the cups to show certain novel guiding means for a filament.

Fig. 9 is an enlarged view showing a plurality 35 of filaments carried by the filament packages.

Fig. 10 is a similar view showing how the filaments are twisted together to form a strand.

Fig. 11 is a similar view showing a section of a 40 finished cable after the strands are twisted together.

Fig. 12 is a combined elevational and sectional view showing the construction of the upper part of the skirt for a spool and the take-up mechanism for taking up the finished cable.

Fig. 13 is a sectional plan view on the line 45 13—13 of Fig. 12.

Fig. 14 is an elevational and sectional view similar to Fig. 12 showing certain details of construction.

Fig. 15 is a sectional plan view on the line 50 15—15 of Fig. 14.

Fig. 16 is a sectional elevational view showing certain features of the bobbin-carrying mechanism.

Fig. 17 is a plan view of the same. 55

Fig. 18 is a side elevational view of certain of the parts shown in Fig. 16.

Fig. 20 is a sectional elevational view on the line 20—20 of Fig. 19.

Fig. 21 is a sectional elevational view on the line 21—21 of Fig. 19, and

Fig. 22 is a fragmentary elevational view to show certain details of construction.

Referring to the drawings in detail, the invention will now be described.

End frames 2 and 4 are provided which are held in spaced apart relation by upper and lower side rails 6 and 8 respectively. These rails may be of any length and are arranged to space the end frames apart any desired distance so that a number of separate twisting units represented by 10 may be associated with the supporting structure formed by the end frames and rails mentioned. In this way it is possible to provide any desired number of the units on one or both of the upper rails and thereby form a compact rigid construction. The different units may be made to operate at different speeds and to produce different cables or cords and any certain unit may be operated individually since they are independent of one another.

Each unit 10 consists, as will be described, of a plurality of rotatable package spindles disposed about a central or main spindle, feed-out mechanism, and lower take-up and bobbin winding mechanism. This provides a structure whereby each unit may be operated independently of the other and thus in a general way the machine consists of a plurality of separate cable-producing mechanisms with certain mechanism common to all the units for causing bobbins to traverse or move up and down relative to the take-up mechanisms whereby finished cables may be fed onto a number of bobbins simultaneously.

Supporting brackets 18, one for each of the units are secured to the upper rails 6. These support a central motor 20 and a plurality of package motors 22 disposed concentrically around the central motors.

The package spindles and associated parts are of the same construction so that one only need be described.

The package motor 22 includes a suitable housing supported by a part 20' associated with the bracket 18. The housing of the motor encloses a stator element 26 and a rotor element 28, the latter of which has associated therewith a package spindle 31. With the rotor element of the motor in rotation, the spindle 31 is rotated thereby and a cup or pot 30 is suitably fixed to the spindle so as to be rotatable therewith.

The spindle at its upper end is provided with a transverse opening 32 and an axial opening extending from the upper extremity of the spindle into the opening 32. An inertia disc 34 is rotatable relative to the spindle 31. This is frictionally driven by the spindle through the means of frictionally engageable members 36 and 38. A sleeve 40 is relatively rotatable on the spindle and is receivable in a core 42 of a package indicated by dash lines P. The core and the package may rotate relative to the spindle to allow material to be drawn from the package as the spindle rotates. The package core 42 is rotated through discs 36 and 38.

When the machine is used for making cables or cords for tires, the package P preferably includes a plurality of yarns wound onto the core

42 in parallelism so that three separate yarns may be unwound from the package simultaneously. It will be understood that the package and its core is slipped down over the sleeve 40. When the yarn has been removed from the package the empty core may be withdrawn and a new package placed on the spindle.

One or more guides such as 44 are located inside the shell 30. The guide is preferably formed from resilient wire to have vertically disposed side legs 46 and a horizontally disposed transverse connecting part 48 at the upper ends thereof. The extremities of the member 46 are secured in some suitable manner to the wall of the cup. The part 48 of the guide is relatively close to the inside wall of the cup and the guide being more or less flexible or yieldable permits the yarn to be slipped behind the guide.

As has been stated, a package may consist of a plurality of separate filaments or yarns E. In this case there are three separate filaments wound onto the package so that they are drawn from the package in the parallel relation shown in Fig. 9. The parallel filaments E are led from the package P beneath the guide or guides 44 and then upwardly through the transverse opening 32 in the end of the spindle and through the axially disposed opening thereof and upwardly onto the over feed-off mechanism, presently to be described, and then into the twisting head.

The central motor 20 has a hollow spindle 50 extending upwardly therefrom which is journaled in a quill or extension 52 associated with the motor 20. An extension 54 associated with the quill extends thereabove and supports a plurality of feed-off devices as well as a twisting head mechanism. There is one feed-off device for each of the package spindles and only one therefor need be here described.

A hub 56 is carried by the member 54 and has a plurality of outwardly extending arms 58 with which the feed-off devices are associated.

A driving gear 60 is carried by the upper end of the rotatable hollow spindle 50 and a stud 62 is associated with each of the arms 58. A gear structure 64 is rotatable on the stud 62 which is in mesh with the driving gear 60. A feed-off drum 66 is screw threaded on the gear 64, a portion of which extends outwardly from the arm, all as shown. The threads of the gear and drum are so arranged that the drum 66 may be unscrewed from the gear 64 by rotating the drum in the direction of its normal direction of rotation. With a drum of a certain diameter being driven at a certain speed it will be apparent that it will feed off a predetermined length of strand. To vary the rate of feed-off it is possible to employ drums of different sizes.

A grooved wheel 68 co-operating with the drum is mounted for rotation on a suitable stud of the arm so that the twisted elements leading from the end of the spindle 31 and after they are twisted may be led or wrapped alternately around the members 66 and 68. In this way it will be possible to contact twisted-together elements a number of times with the feed-off drum to safeguard against slipping and maintain a constant and uniform rate of feed.

A tubular member 70 is associated with the member 56 and mounted thereon is a tubular conical shaped head 72. Wedge members 74 within the head 72 are formed to provide a relatively smooth central axial opening or bore for receiving strands for a cone 76 and spring 78 all as shown. This is so the members 74 are yield-

ingly held in their upper position and co-operate to form the strand receiving central opening, facilitating twisting of the strands.

Manually engageable members 80 are associated with the members 74 and slide in slots in the member 72 as shown so that the members 74 may be pressed downwardly to enlarge the opening which receives the cord and release the cord from sidewise pressure.

10 A tension device 82 is associated with each of the arms 58. This tension device is preferably made from resilient material such as wire which is coiled intermediate its ends to provide flexibility. One end 84 is secured to the arm 58 and its other or inner end extends upwardly and inwardly towards the axis of the shaft 50 with a strand-receiving eye such as 86 provided on the inner end. The tension device is preferably so constructed that normally it tends to assume the 20 dotted line position shown but as will appear in the operation of the machine it is drawn downwardly by the strand's passing through the eye thereof and functions to tension the strand and eliminate slack therein.

25 The take-up mechanism associated with the lower end of the spindle of the central motor will now be described in detail with reference to Figs. 12 to 15, inclusive.

As will be seen, the lower end of the hollow 30 motor shaft 50 extends below the motor 20. A casing 89 is carried by this lower end of the spindle 50 which may consist of secured together parts 90 and 92. A shaft such as 94 is suitably journaled within the casing as by bearing 96 35 and carries on its lower end a grooved take-up wheel 98. A drive gear 100 is associated with the lower end of the housing of the motor so as to be non-rotatable. A shaft 102 is disposed on an axis opposed to the plane of the axis of the central 40 spindle 50 and is rotatable in bosses or bearings 104 within the shell.

A gear 106 associated with the shaft 102 meshes with the gear 100. Another gear 108 fixed to shaft 102 is in mesh with a gear 110 fixed to the 45 shaft 94 so that as the casing 89 is rotated by spindle 50, the shaft 94 and drum 98 are rotated. A drum 95 similar to drum 98 is rotatable on a stud 97 carried by part 92.

50 A lead-out opening 112 for the cable is provided through shaft 50 and a part 116 extending below the casing. A cable such as C may be led outwardly from the center of the spindle 50 and wrapped around the take-up drums 95 and 98 which, as one is driven at a certain speed, will 55 take up the twisted cable at a certain rate.

A flywheel 115 is supported from the part 116 below the casing 89 and a tubular shell-like skirt 118 extends downwardly from the member 114 as shown. A guide member 120 provided with 60 an opening therethrough, as shown, is associated with the flywheel 115 for receiving the cable from the drums 95 and a guide eye 124 is carried by the skirt adjacent its lower end. This is so a cable C may be led downwardly through the skirt and guided for winding onto a bobbin such as B which is moved up and down relative to the skirt so the winding will be systematic.

65 As will be later explained, elements from the package spindles are twisted to form strands and then a plurality of the strands are twisted to form a main cable or cord which is then wound onto a bobbin. The detail operation will be hereinafter more fully described but the mechanism for causing the bobbin to move up and down relative to the skirt will be described at this point.

70 A motor 130 is carried by one of the end frames such as the frame 2 at the left in Fig. 1. A shaft 132 of the motor carries a worm 134 which is in mesh with a gear 136. This gear 136 has associated with it a worm, not shown, which in turn is in mesh with a gear 138 of a shaft 140.

A clutch member 142 is slideable, but non-rotatable, on shaft 140 so as to be shiftable up and down to engage and disengage a mating clutch member 144. A lever 146 forked at its end, as shown, is carried by a shaft 148 which is oscillated by means of an operating lever 150. A cam 152 is associated with clutch member 144 and has a suitable groove which receives a roll or pin 154 of a vertically reciprocable rack 156. A shaft 160, journaled in the end frame 2 has a gear 162 fixed thereon which meshes with the rack 156. When the clutch members 142 and 144 are brought into operable engagement so that the cam 152 is operated by means of the 20 motor and gears the rack 156 is moved up and down to oscillate the shaft 160.

A shaft 164, rotatable in bearings 165 and 166, carries a hand wheel 168 on its upper end and a gear 170 on its lower end which is in mesh with a gear 172 of shaft 140. This is so the shaft 160 may be oscillated manually.

25 A wheel or drum 180 is carried by shaft 160 and a flexible member such as a chain 182 is suitably secured thereto intermediate its ends. As shaft 160 and member 180 are oscillated, opposite ends of the chain are raised and lowered. Slidable rails 184 are fixed to the ends of the chain 182 and have brackets 188 associated therewith which are slidable on rods 190 so that the rails 35 30 may be raised and lowered by oscillation of shaft 160.

35 Spool carrier arms 196, one for each twisting unit, are fixed to longitudinal shafts 198 which are oscillatable in parts 200 associated with rails 40 184. These arms are movable by oscillation of shaft 198 from an upper position to a lower dotted line position shown in Fig. 3. The mechanism to bring about oscillating movements of the arms 196 will be later described, it being sufficient to say for the present that the rails 184 are moved up and down to carry the arms 196 up and down whereby the bobbins such as B carried by the arm may be moved up and down relative to the skirts. This is so a finished cable may be 50 properly served onto the bobbins.

45 The arms 196 are alike and only one of them will be described in detail, reference being had particularly to Figs. 16, 17 and 18. A spider-like member 210 has resilient members 212 associated therewith and is receivable in a ring-like portion 214 at the end of the arm. This is so the member 210 is yieldable in the portion 214. A depending hub 216 of the member 210 has a 55 spindle 218 rotatable therein. A member 220 is associated with the spindle 218 and has tongues 222 receivable in slots which may be provided in the lower flange of a bobbin B.

60 A plunger member 216 is urged upwardly in member 210 by means of a spring 219 and carries on its upper end a friction member 217 which may bring up against the lower side of the bobbin. The plunger is slideable and oscillatable relative to member 210 and has an outwardly extending grip portion 224 which works on a cam face 226.

65 As the member 224 is moved to the left from the position shown in Fig. 18 it is moved downwardly against the action of spring 219 so as to bring the friction part 217 away from the bob- 70 75

bin. When returned to the position shown in Figs. 16 and 18 the cam face is arranged so that spring 219 forces the member 216 upwardly whereby the friction member 217 frictionally engages the bobbin to hold it against or retard its rotation.

The operation of the machine insofar as it has been described will now be explained with particular reference to a single unit.

10 Packages P are placed on each of the package spindles and each package may include a plurality of elements E such as cotton yarn wound in parallelism thereon. Three such elements on each package have been found to produce good 15 results.

The elements E from each of the packages are led through the guides 46 on the inner faces of the cups 30 and then upwardly through the openings in the ends of the package spindles and onto 20 the feed-off devices. On the feed-off devices, the elements are served back and forth alternately on the grooved wheels and feed-off drums 68 and 66 and are then led through the eyes in the ends of the tension devices 82 and downwardly through 25 the twisting head at the top of the central hollow spindle. The elements are passed through the spindle 50 of the central motor, out the opening 112 at the lower end of the spindle, served around the take-up member 98 and through the 30 vertical opening 120 in the flywheel 115 and finally through the guide eye 124 at the bottom of the skirt onto the bobbin B. The central and package motors are put into operation so that the spindles and their associated cups are rotated 35 while at the same time the lower skirt and its associated part are rotated relative to the bobbin which moves up and down within the skirt.

Various results may be obtained or various 40 combinations may be employed to produce cables or cords of different types but by way of explanation it will be stated that the upper package motors may operate at a speed of approximately 7492 revolutions per minute while the central motor spindle may operate at a speed of approximately 3600 revolutions per minute. As the spindles 31 rotate, the packages associated therewith are rotated so that the elements from a package are twisted one about the other resulting in a strand such as S being formed from the 45 elements of each package. The strands S are twisted one about the other by means of the twisting head to form a cable and the cable is wound or served on the bobbin within the skirt.

According to one modification of the invention, with the package spindles rotating in one direction and the central spindle rotating in an opposite direction and at approximately the speeds mentioned, the parts are so arranged that the elements from a package are twisted about one 50 another at approximately 18 turns per inch, while the strands are twisted about one another at 8 turns per inch. This produces a finished cable having 10 turns per inch. This is accounted for in this way. The strands are cable twisted in 55 a direction opposite to that in which the elements are strand twisted so that in twisting for the cable formation a certain number of twists are removed from the strands.

The gears and other mechanisms constituting 60 the feed-out for the strands and the take-up for the cable are constructed to maintain a definite predetermined rate of feed-out with respect to the rate of take-up. This is so the correct amount 65 of twisted strands may be provided to accommo-

date the speed of take-up without slackness or undue tension.

The feed-off and take-up rates are not the same. With the speeds and turns given the take-up rate is 450 inches per minute while the feed-off speed is some less or about 416 inches per minute. By maintaining these relative rates it is possible, since the strand twisting removes a certain number of the twists produced by twisting the elements about one another, to provide 10 the desired tension, all to the end that cord or cable of uniform characteristics may be produced.

In the initial starting of a unit where untwisted elements are led through the central spindle and through the tension devices 82 some slack is provided. As the spindles start to rotate to twist the elements into strands and the strands into a cable this brings about a shortening of the elements but the yieldable devices 82 flex downwardly to accommodate the shortening tendency 20 without unduly tensioning the elements but yet holding them sufficiently taut for the proper twisting operation.

By changing the relative sizes of the drums associated with the feed-off and take-up mechanisms it is possible to feed out the strands according to the number of turns therein at such a rate as will bring about the correct number of turns in the finished cord.

As has been stated the arms supporting the 30 bobbins are moved up and down by the rails 184 so that the finished cord or cable is served onto the bobbins systematically. It is an object of the invention that the bobbin arms and arm shafts supported in rails 184 be oscillated to facilitate removal of the bobbins or to doff the bobbins only when the bobbins and rail are in their lowermost position. This is so the bobbins may be tilted without danger of their striking the skirts.

The mechanism for doing this will now be described with particular reference to Figs. 1, 2, 3, 19, 20, 21 and 22.

Shafts such as 220 are rotatable in bearings 222 carried by frame 2 and carry cranks 224 and gears 226 on their opposite ends. Shafts 228 are 45 rotatable in the bores or cases 200 which carry worms 230 in engagement with gears 232 of shafts 198.

The shafts 220 are urged outwardly by springs 221. When the rails are in their lowermost position the said shafts are forced inwardly to bring the gears 226 into mesh with gears 234 of shafts 228 and then by turning cranks the shafts 198 are oscillated to swing arms 196 either to move bobbins up into the skirts or to remove them 55 therefrom for the doffing operation.

It is desired however that as a safety measure the shafts 198 be releasably locked against oscillation. This locking mechanism will now be described.

A shaft 240 is oscillatable in bearings 242 associated with end frame 2 which has levers 244 on its opposite ends. A lever 246 carried by shaft 240 is connected by a link 248 to one arm 250 of a bell crank (see Fig. 20) which is pivoted at 252 to 65 a bracket 254. Arms 256 are pivoted at 258 to parts 200 and have downwardly depending portions 260 which are forked as shown to receive rolls 262 of slidable lock bolts 264 associated with the cases 200. The lock bolts are spring pressed 70 forwardly into locking position by springs 266 so that their ends enter holes 268 of arms 270 fixed to shafts 198.

A bar 274 is pivoted at one end to the arm 251 of the bell crank and has a member 276 thereon 75

provided with outwardly extending lugs 278. The bar is pivoted at its other end to a link 280 which is pivotally connected to a bracket 282 fixed to frame 4, (see Fig. 1).

5 A lever lock 280 is slidable in frame 2 and its forward end is engaged for reciprocation by a lever 282 carried by shaft 240. The rear end of the lock is arranged to lie in the path of movement of lever 150, (see Fig. 2). As shaft 240 is oscillated the lock 280 is reciprocated simultaneously with the rod 274.

Normally the rails 184 are reciprocated up and down with the arms 270 locked to the parts 200. This is so the bobbin carrier arms are held against movement relative to the rails. When the rails are in lowermost position, the arms 256 are disposed in the position shown in Fig. 22 relative to the collar 216. When in this lower position a shaft 226 may be moved inwardly to engage gears 226 and 234. Then one of levers 244 is operated to reciprocate bar 274 and swing arm 256 to withdraw lock 264 from arm 270 so that the shaft 198 is rotated by rotating member 224.

This moves the bobbin carriers to bobbin-doffing position and the lock 264 may in this rotation slide over arm 270. Prior to oscillating shaft 240 lever 150 in Fig. 2 is moved to the right to disconnect the driving mechanism and as shaft 240 is oscillated lock member 280 advances to lie in the path of lever 150 and prevent its movement while the bobbin arms are in doffing position as well as while they are being moved between said position and a position axially of the skirts.

Thus it will be seen that the elements are 35 twisted into strands which are twisted to form a cable in an efficient manner. The feed-out mechanism for the strands is directly connected to the cable twisting mechanism so that it is possible to feed out the strands and take up the 40 twisted cable at predetermined rates which in conjunction with definite speeds for the spindle facilitates the producing of strands and the subsequent cable which is uniform in all its important strands with the correct tension.

45 The inertia disc rotated by the packages serves to exert a drag on the package and thereby tensions the elements. With a full package the effect of the disc is not important since the weight of the package provides sufficient and 50 desired tension. However, as the elements are drawn from the package the inertia disc comes into play so that the last end of elements are tensioned. In this way the tension on the elements is maintained substantially uniform to 55 contribute to a uniform product.

55 The fly wheel 15 of the skirt functions to rotate the central spindle after the motor current has been cut off. This is desirable as the central spindle simultaneously rotates with the package spindles so that all stop together.

Having described the invention in the form at present preferred what it is desired to claim and secure by Letters Patent of the United States is:

1. In an apparatus of the class described comprising, separate units including means for 65 twisting elements into strands and for twisting strands into cables and for serving cables onto bobbins, a member movable relative to the units including bobbin carriers, means to move said 70 member whereby a plurality of bobbins are moved simultaneously relatively to said units, the said bobbin carriers being movable on said member between cable receiving and doffing positions, means to move said carriers and releasable locking means therefor adapted and arranged to lock 75

the same against movement into doffing position except when the member is in a certain position.

2. In an apparatus of the class described comprising, means for twisting elements into strands and for twisting strands into a cable including 5 a hollow central spindle through which the cable passes, a take-up mechanism at one end of said spindle, a skirt carried by said end of the spindle having means for serving a cable from said take-up onto a bobbin, a member movable up and 10 down in parallelism with the axis of said spindle, a carrier for a bobbin in said member arranged to move a bobbin axially within said skirt the said carrier being movable on said member to move a bobbin between cable receiving and 15 doffing positions only when the carrier is in a certain cable receiving position.

3. In an apparatus of the class described comprising, means for twisting elements into strands and for twisting strands into a cable including 20 a hollow central spindle through which the cable passes, a take-up mechanism at one end of said spindle, a skirt carried by said end of the spindle having means for serving a cable from said take-up onto a bobbin, a member movable up and 25 down in parallelism with the axis of said spindle, a carrier for a bobbin in said member arranged to move a bobbin axially within said skirt the said carrier being movable on said member to move a bobbin between cable receiving and 30 doffing positions, and means to releasably lock the carrier against movements except when the member is in a certain position, means to operate said member and means to operate said carrier.

4. In an apparatus of the class described comprising, means for twisting elements into strands and for twisting strands into a cable including 35 a hollow central spindle through which the cable passes, a take-up mechanism at one end of said spindle, a skirt carried by said end of the spindle 40 having means for serving a cable from said take-up onto a bobbin, a member movable up and down in parallelism with the axis of said spindle, a carrier for a bobbin in said member arranged to move a bobbin axially within said skirt, the 45 said carrier being movable on said member to move a bobbin between cable receiving and doffing positions, means to operate said member and means to operate said carrier, and means to 50 releasably lock the carrier against movements except when the member is in a certain position.

5. In an apparatus of the class described comprising, means for twisting elements into strands and for twisting strands into a cable including 55 a hollow central spindle through which the cable passes, a take-up mechanism at one end of said spindle, a skirt carried by said end of the spindle having means for serving a cable from said take-up onto a bobbin, a member movable up and 60 down in parallelism with the axis of said spindle, a carrier for a bobbin in said member arranged to move a bobbin axially within said skirt, the said carrier being movable on said member to move a bobbin between cable receiving and 65 doffing positions, means to operate said member and means to operate said carrier, and means to releasably lock the carrier against movements except when the member is in a certain position, means to move said member controlled by a movable member, and means to lock said member 70 against movements which is actuated by the carrier locking means whereby the member is locked against movement when the carrier is in a certain position.

6. In an apparatus of the class described com- 75

- prising, means for twisting elements into strands and for twisting strands into a cable including a hollow central spindle through which the cable passes, a take-up mechanism associated with said spindle, a skirt carried by said spindle having means for serving a cable onto a bobbin, a member movable up and down in parallelism with the axis of said spindle, a carrier for a bobbin in said member arranged to move a bobbin axially within said skirt, the said carrier being movable on said member to move a bobbin between cable receiving and doffing positions, and means to releasably lock the carrier against movements except when the member is in a certain position,
- 10 means to operate said member and means to operate said carrier.
7. In an apparatus of the class described comprising, means for twisting elements into strands and for twisting strands into a cable including a hollow central spindle through which the cable passes, a take-up mechanism at one end of said spindle, a skirt carried by the spindle having means for serving a cable onto a bobbin, a member movable up and down in parallelism with the axis of said spindle, a carrier for a bobbin in said member arranged to move a bobbin axially within said skirt, the said carrier being movable on said member to move a bobbin between cable

receiving and doffing positions, means to operate said member and means to operate said carrier, and means to releasably lock the carrier against movements except when the member is in a certain position.

8. In an apparatus of the class described comprising, means for twisting elements into strands and for twisting strands into a cable including a hollow central spindle through which the cable passes, a take-up mechanism at one end of said spindle, a skirt carried by said spindle having means for serving a cable onto a bobbin, a member movable up and down in parallelism with the axis of said spindle, a carrier for a bobbin in said member arranged to move a bobbin axially within said skirt, the said carrier being movable on said member to move a bobbin between cable receiving and doffing positions, means to operate said member and means to operate said carrier, and means to releasably lock the carrier against movements except when the member is in a certain position, means to move said member controlled by a movable member, and means to lock said member against movements which is actuated by the carrier locking means whereby the member is locked against movement when the carrier is in a certain position.

RAYMOND E. GETCHELL.
